H. G. MARTIN,
TELEGRAPHIC SENDING MACHINE,
APPLICATION FILED AUG. 4, 1917.

1,260,008.

Patented Mar. 19, 1918.

UNITED STATES PATENT OFFICE.

HORACE G. MARTIN, OF RUTHERFORD, NEW JERSEY.

TELEGRAPHIC SENDING-MACHINE.

1,260,008.

Specification of Letters Patent. Patented Mar. 19, 1918.

Application filed August 4, 1917. Serial No. 184,401.

To all whom it may concern:

Be it known that I, HORACE G. MARTIN, a citizen of the United States, residing at Rutherford, in the county of Bergen, State 5 of New Jersey, have invented a new and useful Improvement in Telegraphic Sending-Machines, of which the following is a specification.

My invention relates to improvements in 10 telegraphic sending machines for sending messages, of the same general character and purpose as set forth in my prior Patents No. 842,154, dated January 22, 1907, and No. 1,043,449, dated November 5, 1912.

15 Referring to the drawings, Figure 1 is a front elevation of one embodiment of my improved telegraphic sending machine; Fig. 2 is a side elevation of the same, looking toward the left in Fig. 1; Fig. 3 is a 20 sectional view on the line 3—3, Fig. 1, looking downward; Fig. 4 is a similar sectional view of a portion of the moving parts of the apparatus, on the line 4—4, Fig. 1, presently to be explained; Fig. 5 is an 25 oblique or diagonal view, partly toward the left and partly downward, Fig. 1, of the moving or operative parts of the apparatus.

In the preferred construction I provide 30 a metal base 1, having preferably four rubber feet, 2, which rest upon the table and keep the apparatus in equilibrium without the necessity of clamps or screws. An upright frame or base 3 is secured to the base 2 by screws 4, 4, Fig. 1, this construction 35 being employed rather than that of casting the parts 1 and 3 integrally.

A shaft 5 is secured in the upright 3, on which is placed a main lever 6, capable 40 of being moved from left to right upon the axis 5. A ring 7, held in place on shaft 5 by a locking screw 8, Fig. 2, prevents lever 6 from slipping off said shaft. Two studs 9 and 10 are cast on upright 3. A screw 11 with lock nut 12 is inserted in lug 9, and a 45 similar screw 13 with lock nut 14 is inserted in lug 10, Fig. 1, which screws and nuts are adjustable stops to control the movement of the upper end of lever 6 from left to right. The upper end of lever 6 is 50 normally held against stop 11 by a spring 15 near its lower end, whose tension can be varied by means of a screw 16 and thumb nut 17.

A shaft 18 is secured in lever 6 near its upper end, which serves as an axis on which 55 to move a hand lever 19, to the lower end of which pieces of insulating material 20 are secured by a bolt 21 for operating the apparatus, and in the upper end of which is inserted a screw 19. A lug 22 projects 60 from the side of lever 6 (side view, Fig. 2, end view, Fig. 1), against which the lower end of lever 19 is normally held by a spring 23, bolt 24, and the tensioning thumb nut 25. These parts are illustrated in greater 65 detail in Fig. 4.

In the upper end of lever 6 is secured a flat, vibrator spring 27, seen sidewise in Fig. 2 and edgewise in Fig. 1. To the other end of spring 27 is secured a vibrator bar 70 28, whose upper end normally rests against a lug 29, preferably integral with upright 3. On bar 28 is a weight 30 which is held on the bar by two pins 31, but is capable of being moved to and held in any desired position up or down said bar by means of the thumb screw 32, Fig. 1. To bar 28 is fastened in any convenient manner a small metal piece 33, to which is secured a flat spring 34, parts 33 and 34 being seen sidewise, Fig. 2, and edgewise, Fig. 1. Spring 34 carries at its upper end a contact point 35.

A binding post 40 (see Fig. 2) is secured without insulation to the rear side of upright 3 by means of a thumb-nut 41 for attaching an electrical conductor 42. A second binding post 43 is likewise secured to upright 3, but insulated therefrom, for securing a second electrical conductor 44. Post 43 and the manner of securing the 90 same to and insulating it from part 3 are shown in greater detail in Fig. 3. Said post passes through a bushing 45 and washers 46, 46, of insulating material, preventing contact between said post and upright 3. 95

A switch contact 47, Fig. 3 (dotted lines, Fig. 1), is also inserted on post 43, and the parts are held together by washer 48 and nut 49. The electrical conductor 44 is secured to said post by thumb nut 50. At 100 the other end of post 43 is a screw 51 which may be held in any position to which it is moved by the thumb-nut 52, and it has inserted in its end a suitable contact point 53. A switch 54, having an insulated handle 55, 105 is secured to the rear side of upright 3 by a

bolt 56 and spring 57, Figs. 1 and 2. When said switch is open, Fig. 1, the apparatus is operative; but when it is closed, Figs. 2 and 3, the current flows directly between 5 42 and 44 through parts 40, 3, 54, 47, 43, and the apparatus is inoperative.

The operation of the apparatus in the sending of telegraphic messages may now be readily understood. The parts being in 10 their normal position, shown in Fig. 1, and assuming that the electrical current will flow through the conductors 42 and 44 as indicated by the arrows, when the operator desires to send a message, he moves hand 15 pieces 20 and the lower end of lever 19 to the left, Fig. 1, compressing spring 23, and the upper end of said lever to the right, said lever revolving on axis 18. By said movement screw 19^a, which may be adjusted 20 to the right or left as desired, striking the upper end of spring 34 moves it to the right and brings the contacts 35 and 53 together. The circuit is thus closed, and the current 25 flows through the machine by way of conductor 42, upright 3, shaft 5, lever 6, spring 27, bar 28, part 33, spring 34, contacts 35, 53, screw 51, post 43 and conductor 44 to the line. This operation of the machine sends an impulse over the line which 30 continues until the operator releases pressure against the hand pieces 20, whereupon spring 23 returns lever 19 to the position shown in Fig. 1, and spring 34 separates the contacts 35, 53. Further movements of 35 hand pieces 20 to the left and then releasing pressure thereon, sends more impulses over the line. This is the operation for sending the dashes of a telegraphic message. In order to send the dots of a message, the operator moves hand pieces 20 to 40 the right, bringing the upper end of lever 6 against the right hand stop 13, by means of lug 22, which movement also throws spring 27, bar 28 and parts 30, 31, 32, 33, 34, 35 to the right and causes them to vibrate from right to left upon spring 27, which vibrations continue while the upper 45 end of lever 6 is held against stop 13. These vibrations cause a series of makes and breaks between contact points 35 and 53, the number depending upon the length of time which the operator holds the lever 6 against stop 13. For sending a single dot he holds the lever in that position but an instant, 50 and for making more dots he holds it there a longer or shorter time according to the number desired. On releasing pressure against hand pieces 20, spring 15 returns lever 6, and all the parts connected 55 thereto to their normal positions shown in Fig. 1. After each operation vibrations of bar 28 and connected parts, including contact 35, are stopped by said bar coming against lug 29. In the making of dots the

current flows through the mechanism between conductors 42 and 44 in the manner pointed out above.

While I prefer that my within described apparatus stand in a vertical position, as indicated by Figs. 1 and 2, it is capable of 70 successful operation in a horizontal position, the front side of Fig. 1, left hand side of Fig. 2, being in such event the upper side.

I claim:

1. In a telegraphic sending machine, the combination of a base, a shaft secured to the base, a main lever rotating on said shaft, a shaft secured to said main lever, a hand lever rotating on said shaft and having 80 means for its operation located between said shafts, a vibrator mechanism attached to said main lever and adapted to vibrate after said main lever has come to rest, an electrical contact secured to and insulated from 85 said base, an electrical contact operated by movements of said vibrator mechanism, and means whereby said main lever and said vibrator mechanism may be operated by movement of the hand lever in one direction to 90 effect a series of makes and breaks between said contacts after said main lever has come to rest.

2. In a telegraphic sending machine, the combination of a base, a shaft secured thereto, a main lever rotating on said shaft, a shaft secured to said main lever, a hand lever rotating on said shaft and having means for its operation located between said shafts, an electrical contact secured to and insulated from said base, an electrical contact connected with said main lever and means whereby a series of makes and breaks between 95 said contacts may be effected by movement of said hand lever in one direction 100 to 105 without operating said main lever.

3. In a telegraphic sending machine, the combination of a base, a shaft secured thereto, a main lever rotating on said shaft, a shaft secured to said main lever, a hand lever rotating on said shaft and having means for its operation located between said shafts, a vibrator mechanism connected to said main lever and adapted to vibrate after 110 said main lever has come to rest, an electrical contact secured to and insulated from said base, an electrical contact connected to said vibrator mechanism and means whereby a series of makes and breaks between 115 said contacts may be effected through the movement of both said levers, and another series 120 may be effected by movement of said hand lever only.

4. In a telegraphic sending machine, the combination of a base, a shaft secured thereto, a main lever rotating on said shaft, a shaft secured to said main lever, a hand lever rotating on said shaft, vibrator mecha- 125

nism connected to said main lever and adapted to vibrate after said lever has come to rest, an electrical contact connected to and insulated from said base, an electrical contact vibrating with said vibrating mechanism, and means whereby said contacts may be caused to effect a series of makes and

breaks to produce the dots of a message through movement of one end of said hand lever in one direction, and to effect another series to produce the dashes of a message through movement of the opposite end of said hand lever in the same direction. 10

HORACE G. MARTIN.
